UNITED STATES PATENT OFFICE

FRANK DORSON WILLIAMS, OF LOS ANGELES, CALIFORNIA

AIRCRAFT

Application filed October 21, 1927, Serial No. 227,727. Renewed March 14, 1931.

An object of this invention is to provide an air ship that is more fully under the control of the navigator than any other air craft heretofore made and to minimize danger of aerial navigation over both land and sea and in both fair and foul weather.

This invention relates to air craft having parallel rigid, elongated aerial floats and an oscillatable propeller adapted to operate for propulsion and to assist in ascent and descent.

The invention is broadly new, basic and pioneer in that the rigid elongated aerial floats are rigidly spaced apart by spaced apart pairs of spaced apart aerial gliding planes or wings, each pair comprising an upper and a lower gliding plane spaced apart vertically; the upper gliding planes being spaced apart and extending over the tops of, and over forward and rearward zones of the space between, the aerial floats; and the lower gliding planes being fixed to and spacing apart the hulls of the aerial floats at such zones; oscillatable propellers adapted to direct air streams horizontally between the parallel floats and aslant between the upper and lower planes for propulsion at a horizontal adjustment, and upward or downward at other adjustments respectively fore and aft and between the floats and between the pairs of planes, obliquely, for ascent and descent.

Other objects are to minimize flight impeding air resistance; to insure stability in the air and also on water, and to facilitate guiding the craft and turning it around while in flight.

Another object is simplicity, and cheapness, and ease of assembly and operation.

Another broadly new, basic and pioneer feature is the provision of rudders both fore and aft of the craft and means for simultaneously operating all the rudders so as to give the navigator greater control of the craft and enable him to turn the craft in minimum space and to counteract drifting action of side winds while the craft is being advanced by the propelling means.

Other objects, advantages and features of invention may appear from the accompany-

ing drawings, the subjoined detailed description and the appended claims.

The accompanying drawings diagrammatically illustrate the invention.

Figure 1 is a fragmental diagrammatic top view of an air cruiser constructed in accordance with this invention in one of its forms.

Fig. 2 is a longitudinal section on the vertical planes indicated by irregular line $\alpha 2$, Fig. 1.

Fig. 3 is an axial section on the vertical plane indicated by line $\alpha 3$, Fig. 1.

Fig. 4 is a cross section on line $\alpha 4$, Figs. 2 and 3, looking rearwardly.

Fig. 5 is a cross section on line $\alpha 5$, Figs. 2 and 3, looking rearwardly.

Fig. 6 is a diagrammatic front view of the air cruiser shown in Fig. 1; broken lines indicate some of the interior parts.

Fig. 7 is a top view on a larger scale than Fig. 6, of the combined propeller and elevator attached to the air floats, fragments of which are shown.

Fig. 8 is a front elevation on the scale of Fig. 7, of the combined propeller and elevator and its adjuncts in place in the craft appearing in Fig. 2, fragments of which craft are shown.

Fig. 9 is a side elevation of what is shown in Fig. 8 as viewed from section line $\alpha 9$, Fig. 8.

Fig. 10 is a diagrammatic representation of one of the elements installed at top and sides of the craft to act as rudders and elevators, stabilizers and lee control.

Fig. 11 is a diagrammatic view, partly in section, on line $\alpha 11$, Fig. 10.

Fig. 12 is a view from the right of Figs. 10 and 11.

Fig. 13 is a fragmental detail of the construction between the tube and one side of one of the floats looking back as viewed from section line $\alpha 13$, Fig. 14.

Fig. 14 is a side view from line $\alpha 14$, Fig. 13.

Fig. 15 is a side elevation of a reversible motor and propeller.

Fig. 16 is a diagrammatic top view of another form of air craft constructed in accordance with the principles of this invention.

Fig. 17 is a diagrammatic side elevation of the air craft shown in Fig. 15.

Fig. 18 is a diagrammatic front view on reduced scale, of the air craft shown in Figs. 5 16 and 17.

In Figs. 1 to 6 the aerial floats 1, 1a, are constructed with elongate shells 2 having compartments as at 3, 4, 5 and 6 separated from each other by bulkheads 7; and each compartment is shown as filled by duplex gas containers 8 and 9, the outer container 8 enveloping the inner container 9 and provided with a valved inlet 10 for the purpose of filling said outer container 8 with helium gas; the inner container being provided with a valved inlet 11 for filling said inner container with hydrogen gas, so that the hydrogen gas container is practically enveloped by the helium gas, thus practically insuring the hydrogen gas against ignition. Any desired number of compartments may be employed, the same being separated from each other by the bulkheads 7, and the gas containers may be bags of silk or other material or approved appliance of other forms and material.

The shells 2 are preferably of aluminum or other suitable metallic construction, but any suitable material may be employed.

The rudder may be operable by any suitable means, as by the cables at 12.

The shells 2 are connected by rigid upper aerial planes or gliding wings 13, 14 and lower aerial planes or gliding wings 15, 16, that are rigidly fixed to the shells fore and aft, above and below the horizontal mid plane a—a of the craft.

Between the wings there are mounted suitable braces as at 17 which are also fixed to the shells to hold the same from rolling relative 40 to each other.

Said shells are constructed with a blunt, convex nose 18 extending from the forward tip 19 to the zone 20 of maximum cross section with the greater length 21 tapering rearwardly from such zone and terminating in a blunt, convex tail 22.

23 indicates the motor shell, 23' the supporting ring therefor, 24, the motor, 24a the motor shaft, and 25 the propeller on such shaft; all of which are mounted in an oscillatory motor suspension or frame 26 comprising a short tube 27 having hollow trunnions 28 journaled by bearings 29 and 30; said bearings 29 being respectively fixed at one end and being in journalled relation to the oscillatory frame or motor suspension 26, which also comprises blade like spokes 26a connecting the motor shell ring 23' to the tube 27 on which is mounted by suitable means, as struts 27', an elevator plane 27a that is in fixed relation to the oscillatory frame and that serves as an elevator to raise or lower the craft at such angle to the horizon, as may be determined by adjustment of the oscillatory frame with its propeller.

When the craft is under way the gliding wings support it irrespective of the lighter-than-air floats.

The motor suspension and its axial support through trunnions 28, and bearings 29 and 30, together with the lower gliding plane 15, constitute a frame rigidly connected to the aerial floats and forming a support between such floats to carry the oscillatable propeller.

Any suitable means, as the wheel 31, gearing 32, shaft 33 turned thereby, worm gear 34, and segment 35 fixed to the oscillatory frame may be employed to give direction to the engine and its shaft and the air stream 81 from the propeller; and the direction may be changed through any desired angle to the horizon within 45 degrees, more or less up or down, in the plane of the axis of oscillation 82 of the engine.

The tube 27 may be of any suitable length according to the judgment of the constructor and is shown in Figs. 2 and 6, as mounted with the oscillatory elevator plane 27a between the upper and lower glider wings both 91 fore and aft.

The oscillative controlling means may be of any suitable and approved type, and may be operated by the navigator from within the control cabin 36 in the forward part of 92 one of the lighter-than-air floats or from any other suitably located station.

37 indicates an observation port or outlook, which is shown, as projecting from a wall of one of the lighter-than-air floats and said outlook is provided with transparent panes 38, 39, 40 and 41 arranged in angular relation to each other; the top and bottom panes 38 and 40 sloping towards each other and the front and rear panes 39 and 41 therebetween, slanting toward each other and the four panes meeting centrally at 42, thus giving the navigator a clear view through the port or window 37, up, down, front and rear.

Additional motors 43 may be provided and arranged to oscillate 180 degrees more or less, so that they may be turned completely over from front to rear. Such engines may be mounted on top of the gliding wings 13, 14 or on 13', 14' as more particularly indicated 11 in Figs. 15, 16, 17 and 18. It is understood that the same are oscillatable after the fashion shown in Figs. 13 and 14.

The rudders 45 and stabilizers 46 are of practically the same construction, being provided with braces 47; the vertical rudders being oscillatable on vertical axes and the stabilizers on horizontal. The rudders direct the course of the craft and act after the manner of sails to set up a resolution of the forces of side winds, if any, and the air stream, or air projected through the air directing tubes by the main propellers. Quick turns may be made by turning the forward rudders in one direction and the aft rudders 13

in the reverse direction. The same method of managing the stabilizers may be employed in ascent and descent. Levers 48 and flexible connections 49 are after any well known construction approved by the builder.

The shells are provided with storage rooms in the hulls 50 and with passenger cabins 51, above; there being suitable hatches as at 52 to give access to and exit from the passenger

cabins. Hatchways 53, bridges 54 and railings or guards 54' are also shown.

It is understood, that the craft may be furnished at the tips, tail and intermediate portions with any suitable white and colored lights, after the fashion of nautical craft.

The upper glider wings 13, 14 are shown as embedded in the tops of the shells and as projecting beyond verticals not shown, drawn from the sides of the shells, and outward above, and terminating flush with, the planes of the ends of the stabilizers; and it is understood they may be of any suitable length within the judgment of the constructor.

The oscillatory frames, elevator planes, with their tubes, motor frames, motor shafts and propellers may be turned to any practicable angle to the horizon, as from horizontal to an angle of 45 degrees for the purpose of directing the course of the craft to rise from the ground or water or a runway, practically at once, and then by turning to a less incline or a horizontal direction, can move more directly along a horizontal course as will be readily understood.

By turning the engine completely over, the force of the propellers may be applied to stop the forward motion of the craft.

In Figs. 16, 17 and 18, an arrangement for embodying the invention on a larger scale than in Fig. 1, is shown, there being a main lighter than air float 55 and side floats 56, 57, fixed thereto by upper and lower fore and aft gliding planes 13', 14', 15', 16'. Suitable rudders, or lee controls, stabilizers, and means for controlling the same, are also provided as with the form shown in other views. So also with respect to the oscillatory frames, elevators, motors and propellers of the other views, and means for controlling the engine, rudders, lee controls and stabilizers.

The fuel and lubricants may be stored in the hull and supplied to the engines by any well known means as the gas line 58, an oil line 59, and control rod 60 indicated in Fig. 18 as passing through a hollow trunnion from an air float cabin.

In case of the larger craft shown in Figs. 16, 17 and 18 the central air float is of greater size than the auxiliary air floats and the auxiliary floats are on a plane mainly below the mid horizontal axial plane of the larger air float and the cabins and machinery are also located below such mid plane for the provi-

sion of insuring stability of the craft in the air.

It is understood that any suitable bracing inside and outside the shells and including stays 17' shown in Figs. 17 and 18, may be employed within the judgment of the constructor and that the craft may be provided with any suitable anti-friction supports as indicated by the wheels 61.

In practical use the craft will be given its load of fuel, oil, cargo and passengers; the hatches may be closed, and the navigator puts into operation the requisite engines to drive the propellers which he will adjust to an upward angle adapted to lift the craft directly from the surface upon which it rests as from the ground or from the water, without any necessity of running horizontally as heretofore found to be necessary with air craft having gliding planes.

The oscillatory frames will be adjusted to cause the propeller to exhaust air from above and discharge the same downwardly aslant, thus simultaneously diminishing the air pressure above the level of the upward surfaces of the gliding planes and the lighter-than-air floats, and increasing the air pressure below the under surfaces of the lower gliding planes and said lighter-than-air floats. The equilibrium of the air pressures on the upper and lower surfaces being thus destroyed, the excess upward pressure from below assists the lighter-than-air floats to cause the air craft to rise with a movement in the direction opposite to that toward which the air streams are directed by the propellers, and as altitude is reached to escape obstacles on the earth, the propellers 25, and the oscillatory planes 27a, will act upon the air through which the craft is advancing, to assist the upward progress of the craft until the angle of the propellers and oscillatory planes is changed to horizontal adjustment, or to adjustment for descent or ascent.

As the craft rises, the navigator may adjust the angle of the oscillatory frames and their propellers and engines to cause flight at a desired angle or parallel to a horizontal plane and may change the altitude and the angle of flight by operating the oscillatory controlling means.

The upper gliding wings 13 and 14 projecting beyond the floats not only assist in supporting the air craft in flight but also assist in stabilizing the craft so that effective operation of the oscillatory plane is made practicable.

To lessen speed suddenly or to stop, the rudders and stabilizers may be turned cross-wise of the course, and the reversible engines may be turned fore and aft to pull against each other at upward inclinations thus to allow practically vertical descent.

In Fig. 15 the segmental gear 35' extends over a sufficient arc to allow the engine to be

reversed and the oscillating elevator plane shown in the other views is omitted.

I claim:

1. The combination with an air craft frame and the gliding wings and lighter-than-air floats connected to said frame, of an oscillatory frame; a motor carried by the oscillatory frame and provided with a rotary shaft extending in a plane at right angles to the axis of oscillation; a propeller direct-connected to the propeller shaft; an elevator plane fixed to the oscillatory frame in parallelism with the rotary shaft; and means for operating, controlling, and holding stationary, the oscillatory frame.
2. The combination with aerial floats, of a frame rigidly connecting the floats to each other; an oscillatory frame mounted on the connecting frame and arranged between the floats; a motor carried by the oscillatory frame and provided with a shaft at right angles to the axis of oscillation; a propeller between the floats and fixed to said shaft; an elevator plane in fixed relation to the oscillatory frame, and means for causing and controlling the oscillation of said oscillatory frame and for holding it stationary relative to the craft frame.
3. The combination with aerial floats, of a frame connecting the air floats to each other; an oscillatory frame mounted between the floats and on the connecting frame; an elevator plane mounted on the oscillatory frame; a motor carried by the oscillatory frame and provided with a shaft at right angles to the axis of oscillation; a propeller fixed to said shaft; and means for causing and controlling the oscillation of said frame and for holding the same stationary relative to the craft frame.
4. The combination with air floats, of a frame connecting the air floats to each other and spacing them apart; an oscillatory frame mounted on the connecting frame and in the space between the air floats; an elevator plane carried by the oscillatory frame; a motor carried by the oscillatory frame and provided with a shaft at right angles to the axis of oscillation; a propeller fixed to said shaft and located between the floats; and means for causing and controlling the oscillation of said frame and for holding it stationary relative to the craft frame.
5. The combination with an air craft frame and float means in fixed relation to said frame to support the same; of a glider wing fixed to said frame; an oscillatory frame carried by the air craft frame; a motor carried by the oscillatory frame and provided with a rotary shaft extending in a plane at right angles to the axis of oscillation; a propeller located between the floats and direct-connected to the propeller shaft; an elevator plane fixed to the oscillatory frame in parallelism with the rotary shaft; and means for

operating, controlling, and holding the oscillatory frame stationary relative to the air craft frame.

6. The combination with two elongate floats, of a frame comprising gliding wings and connecting said floats to each other and spacing them apart, of a motor having a rotary shaft and mounted to oscillate in a plane between and parallel to the longitudinal axes of the floats; a propeller located between the floats and fixed to the shaft; means to control the operation of the motor; and means whereby the motor and shaft may be caused to oscillate in said plane and also to be held from oscillation while at a determined angle.

7. The combination with two elongate floats, of a frame comprising a glider and connecting said floats to each other and spacing them apart, of a motor having a rotary shaft and mounted to oscillate in a plane between and parallel to the longitudinal axes of the floats; a propeller fixed to the shaft; means to control the operation of the motor; means whereby the motor and shaft may be caused to oscillate in said plane and also to be held from oscillation while at a desired angle; and a tube through which air from the propeller is driven.

8. The combination with two elongate floats, of a frame comprising a glider and connecting said floats to each other and spacing them apart, of a motor having a rotary shaft and mounted to oscillate in a plane between and parallel to the longitudinal axes of the floats; a propeller fixed to the shaft; means to control the operation of the motor; means whereby the motor and shaft may be caused to oscillate in said plane and also to be held from oscillation while at a determined angle; and a tube in which the propeller revolves; said tube being in fixed relation to, and extending around the motor, co-axial to the rotary shaft.

9. The combination with two elongate floats, of a frame comprising a glider and connecting said floats to each other and spacing them apart, of a motor having a rotary shaft and mounted to oscillate in a plane between and parallel to the longitudinal axes of the floats; a propeller fixed to the shaft; means to control the operation of the motor; means whereby the motor and shaft may be caused to oscillate in said plane and also to be held from oscillation while at a desired angle; and a glider fixed to and oscillatable with the motor.

10. The combination with two elongate air floats of a frame and gliding wings constituting means connecting said floats to each other and spacing them apart; a motor provided with a shaft and oscillatable between the floats in a plane parallel to the axes of the floats; stabilizing wings at the sides of the floats; rudders carried by the frame; means to control the motor; means to oscil-

late the motor and its shaft and to hold the same from oscillation; a propeller fixed to the shaft and oscillatable in the space between the floats and between glider wings that are above and below the propeller; means to operate the stabilizer and means to control the rudders.

11. The combination with two elongate lighter-than-air floats, of upper and lower gliding wings fixed to, connecting and spacing apart said floats; the upper gliding wings extending over and beyond the outer sides of the floats to stabilize the craft, and elevator means between the floats.

12. The combination with aerial floats of gliding wings connecting said floats; oscillatory engines mounted on the wings and provided respectively with rotary propeller shafts; elevator planes connected to the engines to oscillate therewith and oscillatable between the floats and between upper and lower gliding wings; propellers on said shafts respectively; means to control the engines, and means to oscillate the engines and their shafts and propellers.

13. An air craft comprising a central aerial float, auxiliary aerial floats alongside the same in a horizontal plane on opposite sides of said floats and spaced therefrom; gliding wings connecting the air floats together, and propellers on said wings to drive the craft.

14. An air craft comprising a central aerial float, auxiliary aerial air floats arranged in a common horizontal plane on opposite sides of, and alongside of and of less diameter than the central float; gliding wings connecting the floats together, and propellers on said wings to drive the craft.

15. Air craft comprising gliding wing-connected floats having cabins; and rudders having vertical axes on the wings, and means to operate the rudders.

16. Air craft comprising lighter-than-air floats, and gliding wings connecting the same; rudders having vertical axes on the wings; stabilizer having horizontal axes on the floats and means to operate the rudders and stabilizers.

17. Air craft comprising lighter-than-air floats; gliding means connecting the floats; a tube oscillatable on such means; means including a hollow trunnion for mounting the tube on the gliding means; a motor mounted in the tube; a propeller adapted to be driven by the motor; means leading through the hollow trunnion for operation of the motor and means for oscillating the tube and controlling and preventing such oscillations.

In testimony whereof, I have hereunto set my hand at Los Angeles, California, this 17th day of October, 1927.

FRANK DORSON WILLIAMS.
